(57) **CLAIM**

The ornamental design for an auxiliary magazine holder for firearms, as shown and described.

DESCRIPTION

FIG. 1 is a frontal isometric view of my auxiliary magazine holder for firearms;

FIG. 2 is a rear isometric view thereof;

FIG. 3 is a top plan view thereof;

FIG. 4 is a bottom plan view thereof;

FIG. 5 is a left side elevational view thereof;

FIG. 6 is a right elevational view thereof; with dashed lines forming no part of the invention showing a firearm, to illustrate the environment;

FIG. 7 is a front plan view thereof, with dashed lines forming no part of the invention showing a magazine, to illustrate the environment; and,

FIG. 8 is a rear plan view thereof.
